UNITED STATES PATENT OFFICE.

FRANK W. MAZSICK, OF NORTH MILWAUKEE, WISCONSIN.

ACETYLENE GENERATOR.

1,407,943.

Specification of Letters Patent. Patented Feb. 28, 1922.

Application filed December 6, 1920. Serial No. 428,739.

To all whom it may concern:

Be it known that I, FRANK W. MAZSICK, a citizen of the United States, and resident of North Milwaukee, in the county of Milwaukee and State of Wisconsin, have invented certain new and useful Improvements in Acetylene Generators; and I do hereby declare that the following is a full, clear, and exact description thereof.

10 My invention refers to carbide gas generators, and has for its object to provide a simple, economical and effective feed mechanism for such generators. The specific object of the invention is to provide a feed 15 mechanism wherein tooth gearing is dispensed with, and the parts are arranged to be so controlled that should the generator bell fail to respond when a charge of carbide is delivered, due to the weakness in its 20 strength, an auxiliary charge will be delivered to reinforce the first charge, whereby the desired quantity of gas is generated to lift the bell.

With the above and other minor objects in view, the invention consists in certain peculiarities of construction and combination of parts as are hereinafter set forth, with reference to the accompanying drawings and subsequently claimed.

30 In the drawings,

Figure 1 represents a sectional elevation of a generator embodying the features of my invention, and

Figure 2 is a cross section on the line 2—2 35 of Figure 1 illustrating more particularly the details of the valve mechanism.

Figure 3 is a section taken on line 3—3 of Figure 1.

Referring by characters to the drawings, 40 1 represents the tank, the lower portion of which constitutes a well adapted to receive the proper quantity of water, and communicating with which is a clean-out pipe 2. The tank is provided with the standard bell 3, 45 having suitable guides 3', it being understood that the bell is adapted to rise and fall in the usual manner. Its lower edge is submerged in a water seal 4, which seal is formed by a jacket 5 that is secured at its 50 bottom to the side walls of the tank. A service pipe 6 extends through the jacket wall 5 and communicates with the interior of the bell, the outer end of which pipe is adapted to be coupled to a suitable supply connection. The top wall of the bell is pro-

vided with a vent valve 7, whereby air is let out of the bell when the parts are assembled.

A bracket 8 extends from the inner side walls of the tank and supports a suitable carbide hopper 9, having an inclined bottom 60 which terminates in a funnel-shaped throat 10. The hopper is also provided with a filling cap 9'. The bottom of the hopper directly over its throat is fitted with a conical skeleton deflector 11, which is arranged 65 to prevent the carbide from clogging at its discharge opening. The throat 10 of the hopper communicates with a similar semi-circular bell 12, which is suitably braced by a strap 12' that is secured to cylinder 9", 70 whereby all of these parts are self-contained. The bell is provided with end walls 13 which form journals for trunnions 14 of a cylindrical valve 15. This valve is formed with a main port 16, which normally communicates with the throat 10 and is so positioned 75 that its delivering mouth is closed by the cylindrical shell 12. A by-pass or auxiliary port 17 communicates with the main port 16 and terminates at the outer wall of the 80 valve shell a predetermined distance from the intake mouth of the main port, this auxiliary port being also normally closed by the shell. The port 16 is of such area as to hold the normal quantity of carbide, which is of 85 standard strength. Hence, when the valve is rotated below the lower edge of the shell, this charge of carbide will be delivered to the water, whereby gas is generated. If, however, the carbide is not of sufficient 90 strength to generate a volume of gas for lifting the bell, the mechanism is arranged to automatically shift the valve, still further, 95 in its direction of discharge, whereby the restricted auxiliary port will come in communication with the throat 10 and deliver a small continuous stream of carbide to the water until such time as sufficient gas is generated to lift the bell. The means for automatically actuating the cylindrical valve 100 comprises an arm 18 which is secured to one of the valve trunnions and is connected by a link 19 to the rocker arm 20, which rocker arm is fulcrumed upon a bracket secured to the apron 9' of the hopper 9. The outer end 105 of the rocker arm 20 is connected to a reciprocative plunger rod 21, which projects above the hopper and is arranged to be engaged by the bell when said bell reaches a low position, due to the gas contained there- 110

in having been reduced in volume. The arm 18 has adjustably secured to its outer end a coil spring 22, the opposite end of said spring being connected to one of the bracket elements. This spring serves to hold the plunger rod 21 upwardly and to also maintain the valve port 16 in its normal position communicating with the throat 10, and the parts are held in register by means of the spring power which tends to rotate the valve until such time as a stop dog 23 carried by the valve comes in contact with the lower edge of the shell 12, as shown in Figure 1.

Attention is also directed to the fact that when the spring acts to restore the valve to its normal position after it has discharged carbide, this stop dog 23 will, in striking the edge of the shell, 12, produce a hammer blow whereby the carbide contained in the hopper above will be slightly vibrated or agitated sufficiently to start it on its feed downwardly into the port 16.

While I have shown and described the novel features of my invention minutely as to detail, it is understood that I may vary the structural features so described within the scope of the claims. It will also be noted that while I have shown a spring for actuating the valve arm in one direction, I may in some instances employ a weight for accomplishing the same results.

I claim:

1. In an acetylene generator comprising a tank and a reciprocative bell; the combination of a carbide feed mechanism comprising a hopper having a discharge throat, a

circular shell communicating with the hopper throat, an oscillatory cylindrical valve nested within the shell, having a main discharge port and an auxiliary port in communication with the discharge port, and means under control of the bell for actuating the valve whereby a predetermined quantity of the carbide is discharged under normal conditions, followed by an emergency action whereby the auxiliary port is brought into communication with the throat to discharge a further quantity of carbide.

2. In an acetylene generator having a tank and bell, a feed mechanism therefor comprising a funnel-shaped hopper having a discharge throat, a semi-circular shell communicating with the throat, an oscillatory cylindrical valve mounted in the shell, having a discharge port normally in communication with the throat at one end and closed by the shell at its opposite end, an actuating lever secured to the valve, a spring connected to the lever for holding the valve in its normal position, a stop dog carried by the valve and adapted to exert a hammer blow upon the shell when the valve assumes its normal position with relation to the hopper throat, a plunger rod connected to the lever and engageable with the bell whereby the valve is actuated in opposition to its spring control.

In testimony that I claim the foregoing I have hereunto set my hand at North Milwaukee, in the county of Milwaukee and State of Wisconsin.

FRANK W. MAZSICK.
